UNITED STATES PATENT OFFICE.

JOSEPH H. PILKINGTON, OF WATERBURY, CONNECTICUT.

HOSE-SUPPORTER.

1,250,499.

Specification of Letters Patent. Patented Dec. 18, 1917.

Application filed June 30, 1917. Serial No. 177,981.

To all whom it may concern:

Be it known that I, Joseph H. Pilkington, a citizen of the United States, and resident of Waterbury, in the county of New Haven and State of Connecticut, have invented certain new and useful Improvements in Hose-Supporters, of which the following is a specification.

My invention relates to new and useful improvements in hose supporters and more particularly to the button stud and plate forming a part of the supporter.

The object of the invention is to generally improve upon this class of device and particularly to design a Hose-supporter button which will be soft and flexible, and which will not require the use of a stud in its make-up or for its attachment to the plate; further to design and construct the parts so as to enable them to be assembled and secured together by a single operation and without the employment of additional parts or material other than the button and plate, and finally to provide a construction which will enable the button to be attached to the plate and by a single operation quickly.

With these and other objects in view the invention resides and consists in the construction and novel combination and arrangement of parts hereinafter more fully described, illustrated in the accompanying drawings, and pointed out in the claims hereto appended, it being understood that various changes in the form, proportion, size and minor details of construction within the scope of the claims may be resorted to without departure from the spirit or sacrificing any of the advantages of the invention.

Similar characters of reference denote like or corresponding parts throughout the several figures of the accompanying drawings forming a part of this specification, and upon which,

Figure 1, shows a top plan view of a sheet metal blank, which has been stamped out in accordance with the requirements of my invention, and to which the button is attached.

Fig. 2, shows a side elevation of the button.

Fig. 3, shows a side elevation of the button and plate assembled and in position to be operated on to secure them together.

Fig. 4 shows a top plan view of the button and plate assembled and secured together to form the completed article.

Fig. 5, shows a bottom plan view of the assembled article shown in Fig. 4.

Fig. 6, is a side elevation of the assembled button shown in Figs. 3, 4 and 5.

Fig. 7, shows a central vertical sectional view taken on line 7-7 of Fig. 4, and

Fig. 8, shows a further plan view of the complete button as seen in Fig. 4, but having a piece of webbing attached thereto.

Referring in detail to the characters of reference marked upon the drawing, A represents a base plate and B the button, which is preferably formed of rubber and as will be noted is made of one solid piece and of special size and shape.

The particular shape of this button will perhaps best be understood from Fig. 2 wherein it will be seen that the sides of the head portion 10 tapers inward slightly from the top to the bottom, thus forming the head wider through its upper top portion than through the lower or shank portion. This narrowest portion of the button comes near the bottom and adjacent to the flange 11, and which flange is of a slightly larger diameter than the upper head part of the button.

The plate A to which the button B is attached is first stamped to form the blank shown in Figs. 1 and 3, and this blank in turn is operated upon to secure it to the shank of the button as will be later described. The blank in question is preferably formed slightly oblong and is provided with oppositely located circular slots 12 and 13 through which the web 14 is threaded for the attachment of the button, to the webbing. A central hole 15 is also formed in this blank and as will be noted from Fig. 1, is slightly elongated, being longest in the direction of the length of the blank. In the assembling for the completion of the article the flange and shank portion of the rubber button are shoved through the central hole 15 of the plate and are adjusted to an upright position with respect to the plate, as shown in Fig. 3. The assembled parts are then secured together by a suitable machine

and with a single operation upon the plate. This operation forms a crease 16 and rib 17 transversely across the central portion 18 of the blank and in a way to materially reduce the size of the central portion and to close the edge of the hole 15 against the shank of the rubber button thereby securing the shank portion of the button within the opening of

the plate by crowding it against the inner ends of the ribs formed upon the under side. This operation also throws down the cross ribs 17 on the under side of the plate to a fullness about equal to that of the thickness of the flange portion of the button and in a manner to support and protect the extended lower end of the same.

When the article is completely formed as shown in Figs. 5 and 6, the webbing 14 may be attached as seen in Fig. 8 to form the complete hose supporter.

Having thus described my invention, what I claim and desire to secure by Letters Patent is—

1. A garment supporter, comprising a sheet metal base-plate having a hole therethrough, a button set in the said hole and a rib formed upon one side of the plate in line with the button to support the shank of the same.

2. A garment supporter, comprising a sheet metal base-plate having a hole there-

through, a button set in the hole, a groove formed in one side of the plate and a rib 25 upon the opposite side and both in line with the button to hold the same.

3. A garment supporter, comprising a button having a relatively narrow shank portion and a flange upon its lower end, a 30 sheet metal base-plate having an elongated central hole therethrough to receive the shank of the button, the said base-plate being transversely creased to form a rib upon the under side in line with the shank of the 35 button and opposite edge portions of said hole being deflected against the shank of the button to support the same.

Signed at Waterbury, in the county of New Haven and State of Connecticut, this 40 28th day of June, A. D. 1917.

JOSEPH H. PILKINGTON.
